[57] **CLAIM**

The ornamental design for a hand pointer for a game or similar article, as shown and described.

DESCRIPTION

FIG. 1 is a top plan view of a hand pointer for a game or similar article showing our new design.

FIG. 2 is a bottom plan view of the hand pointer.

FIG. 3 is an end elevational view taken on line 3—3 of FIG. 1.

FIG. 4 is a cross sectional view taken on line 4—4 of FIG. 1.

FIG. 5 is a cross sectional view on an enlarged scale, taken on line 5—5 of FIG. 1.

FIG. 6 is a bottom plan view of another embodiment of the hand pointer, wherein certain cross-shaped feet are replaced by hemispherical knobs.

FIG. 7 is an end elevational view similar to FIG. 3, but showing the embodiment of FIG. 6 in inverted position.

FIG. 8 is a cross sectional view similar to FIG. 4, but taken through the embodiment of FIG. 6 in inverted position.

FIG. 9 is an enlarged cross sectional view taken on line 9—9 of FIG. 6, partially across the hand pointer.
